UNITED STATES PATENT OFFICE.

JOHN B. DOWNING, OF EAST ORANGE, NEW JERSEY, ASSIGNOR TO BEAVER MACHINE
& TOOL CO. INC., OF NEWARK, NEW JERSEY.

ELECTRIC SOCKET.

Application filed October 6, 1924. Serial No. 741,938.

This invention relates particularly to the type of sockets commonly called plural sockets, which are used to obtain additional outlets from an existing single socket or receptacle outlet.

In sockets of this type that I am familiar with and particularly those in which the female or outlet shells are not moulded into the composition, I have found the objectionable feature of the shells rotating and becoming loose. When these shells loosen, there is a tendency for the various parts of opposite polarity to come into contact with each other and thereby cause a short circuit, which of course might result in serious damage.

In this invention, I have devised means for overcoming this and at the same time provided a structure which is very substantial and at the same time economical to manufacture.

Reference is directed to the drawings in which—

Figure 1— shows the socket assembled in one half of the casing.

Figure 2— is an exterior view of the socket.

Figure 3— is an interior view of the case half.

Figure 4— is a binding screw washer.

Figure 5— is a perspective view of the male shell plug, taken from the top.

Figure 6— is a perspective view of the male shell plug, taken from the bottom.

Figure 7— is an insulating strip.

Figure 8— is a perspective view of the male shell, taken from the base.

Figure 9— is a connector member.

Figure 10— shows a method of interlocking the female shells.

Figure 11— shows the means of connecting the conductor to the lower screw shells.

In carrying out my invention, I employ a casing made from insulating material and composed of two parts which are duplicates of each other. These parts are indicated as 1, Figures 1 and 2. These half casings are preferably held together by screws 2—2^a and nuts 3—3^a. The lower ends of the casings are provided with beads or flanges 4—4^a, which permit the fastening of a shade holder (not shown) to the socket. These beads

also tend to strengthen the casing at this point.

Associated with the casing are screw shells 5—5^a, having flanges 6—6^a, which facilitate the insertion of a lamp or attachment plug.

The base of the screw shells 5—5^a are cut out as at 7—7^a—7^b—7^c; and the case provided with recesses 8—8^a. Passing thru these cut outs and lying within the recesses is an insulating strip 9, which holds the screw shells 5—5^a in place and at the same time prevents them from rotating when a lamp or attachment plug is screwed into place.

To further prevent rotation the shells are interlocked as shown by Figure 10.

A third screw shell 10 is provided for connecting the socket to another socket or outlet receptacle. This screw shell is maintained in place by a plug 11, made of porcelain or other suitable insulating material.

To prevent the rotation of the screw shell 10, and the plug 11, the base of the shell has a rectangular opening 12, and the plug has a rectangular boss 13, which passes thru opening 12 and into a recess 14, in the casing 1.

The base of the screw shell 10, is formed with indentations 15—15^a. Clearances 16—16^a are provided in plug 11, to accommodate these indentations.

The bases of the screw shells 5, 5^a, are slit to form straps 17—17^a.

To provide an electrical path between the screw shells 5—5^a, and 10, wire conductors 18—18^a are passed under the straps 17—17^a and soldered. The opposite ends are located in indentations 15—15^a of shell 10.

To provide the second electrical path of the circuit a U shaped member having projecting arms 19—19^a; a base 20 which has a threaded hole and connecting links 21—21^a is used. This U shaped member is passed thru the opening 22 of the insulator strip 9, then thru the cut outs 7^a—7^b, of the shells 5—5^a and housed in channels 23—23^a in casing 1.

By tightening the screw 24 into the U shaped member it clamps the insulator strip 9 tightly against the base of the shells 5—5^a, which in turn rest against shoulders 25—25^a of casing 1; thus binding the entire group of parts into a unitary structure.

To prevent the screw 24 from becoming loose or turning the head is soldered to a washer 26, having lugs 27-27^a which fit into recesses 28-28^a of plug 11. The solder is shown at 29.

Having described my invention what I claim is:-

1. An electric lamp socket comprising a casing, a male shell and plug, a plurality of 10 female shells, an insulating member passing thru openings in said female shells and lying within recesses in said casing, said insulating member in conjunction with a center contact member and screw, clamping said fe-

male shells rigidly against shoulders in said 15 casing and means for electrically connecting the male shell to the female shells.

2. In a plural electric socket, a plurality of receptacle shells having means to prevent relative rotation between them; said means comprising the remaining edges of a cut away portion of the base section of one of the shells abutting against like remaining edges of a cut away portion of another shell.

Signed by me this 3rd day of October, 25
1924, at Newark, N. J.

JOHN B. DOWNING.
